CLAIM

The ornamental design for a mobile communication terminal display screen with graphical user interface, as shown and described.

DESCRIPTION

FIG. 1 is a front view of a mobile communication terminal display screen with graphical user interface showing a first embodiment of the new design;

FIG. 2 is a second embodiment thereof; and,

FIG. 3 is a third embodiment thereof.

The broken line showing of the device and portions of graphic user interface are included for the purpose of illustrating environmental structure and portions of the article and form no part of the claimed design.

1 Claim, 3 Drawing Sheets
